UNITED STATES PATENT OFFICE.

WILLIAM U. BURGETT, OF DANVILLE, ILLINOIS.

FOOT-POWER HAMMER.

SPECIFICATION forming part of Letters Patent No. 625,870, dated May 30, 1899.

Application filed August 5, 1898. Serial No. 687,836. (No model.)

To all whom it may concern:

Be it known that I, WILLIAM U. BURGETT, a citizen of the United States, residing at Danville, in the county of Vermilion and State of Illinois, have invented certain new and useful Improvements in Foot-Power Hammers, of which the following is a specification, reference being had therein to the accompanying drawings.

10 This invention relates to a blacksmith's hammer or "oliver" operated by foot-power.

The object of the invention is to produce a mechanism by which a hammer may be made to strike a strong blow on an anvil or on any 15 thing on the anvil, in any desirable position on the anvil, the mechanism being quickly adjustable to different positions and capable of striking a good blow in any of its properly-adjusted positions; and the improvement 20 consists in the construction of parts and combination of elements by which these objects are attained.

Figure 1 is a perspective view of an anvil with the improved power mechanism applied. 25 Fig. 2 is a rear elevation of anvil-block, showing bracket 7, cross-bars 11, and connections by which the supporting-bars 10 are shifted in position. Fig. 3 is a partial section and 30 partial elevation of the hammer-head, showing cushion.

The anvil 1 is supported on a block 2, as usual. The block 2 is made a base for the attachment of the hammer-operating mechanism in whole or in part; but to avoid waste 35 of room some of the mechanism may be supported from the floor, as in the drawings.

3 indicates a bent or U-shaped treadle-lever which extends in front and at each side of the block 2 and is pivoted to suitable supports, as at 44. Draw-bars 5 are pivotally connected to the treadle-lever, and these bars 40 are at their upper ends pivoted to intermediate lever 6, which lever is pivoted to a bracket 7, connected to the anvil-block.

45 A pitman or link 8 is connected by a similar pivot to the outer end of intermediate lever 6, and this pitman or link is pivoted to loop 9, which surrounds the hammer-handle. The hammer being pivotally supported, a 50 depression of the swinging end of lever 3 draws on bars 5, which bars rock lever 6 downward, and this draws on pitman 8 and

loop 9 and swings the hammer downward. The bars 5 being pivoted to the outer members of the foot-lever act as braces to support 55 as well as draw on lever 6. The link or pitman 8 is preferably made in form of a truss, as shown, to be as light as possible and at the same time quite stiff. The pivotal connections are preferably bolts passing rather 60 loosely through holes in the bars, levers, &c., to make an easy joint capable of some slight flexibility in sidewise direction.

A frame consisting of two side or supporting bars 10 10, connected by cross-bar 11, is 65 pivoted to the bracket 7 by a pivot passing through said cross-bar into the bracket. This cross-bar has an arm 12 connected to lever 13, and lever 13 is pivoted to block 2, so as to swing or turn on the pivot. Pins 14, projecting from the anvil-block, form rests for lever 13, and as the lever 13 is adjusted between pins 14 the cross-bar 11 is rocked on its pivotal or swiveled connection to bracket 7, so as to raise one bar 10 and lower the other. 70 The connection to bracket 7 is loose, so that the outer ends of bars 10 may be raised or lowered.

The two bars 10 are pivoted to the standard 15 and also to the hammer-handle, as 80 shown. The standard 15 has notches 16, as shown, near its lower end, and one or another of these notches may be engaged on the catch 17, attached to the floor, the lower end of bar 15 passing through a hole in the floor. 85

The hammer-handle 20 is pivoted between bars 10, and below or beyond its pivot a coil-spring 21 draws on the outer end of the handle and on the standard 15. This spring thus pulls down on the outer end of the handle, 90 serving to lift the head 30 of the hammer. The pull of the spring also holds the notches of the standard 15 closely into engagement with the catch 17.

As will be readily understood, the engagement of one or another of the notches 16 on the catch 17 lifts the outer ends of bars 10 more or less. As the outer end of these bars is let down it swings the pivot 23 of the hammer away from the anvil-block at least until 100 the bars 10 come to horizontal position, and this necessarily carries the hammer farther away from the anvil. Thus the vertical adjustment of standard 15 determines to a con-

siderable extent the position of the hammer, and the hammer may be made to reach any position on the anvil within the limit of its adjustment by engaging different notches of standard 15 with catch 17. The downward pressure of the foot on the treadle-lever pulls the hammer down and on the release of the treadle-spring 21 raises the hammer.

The adjustment of lever 13 between pins 10 14 rocks one bar 10 upward and the other downward, causing the pivot 23 to move a little from its horizontal position, and thus causing the blow of the hammer to be at one side or the other of the anvil. The easy fit of the 15 pivots in the holes in the levers or bars permits this slight shift of the parts without difficulty.

The loop 9 is held to handle 20 of the hammer by set-screw 24 and can be moved so as to operate with greater or less leverage. The bars 5 may also be connected to lever 6 at different points. This gives a great range of adjustment, so that the hammer may be made to swing in almost any desired arc. The hammer-pivot 23 is also movable, as at 26.

The hammer preferably consists of a peen or head 31, which has a recess therein in which a rubber or other elastic cushion 32 is placed. The hammer-spindle 33 in this cushion goes 30 through a socket 34 on the handle and is held in by a pin or key 35. The spindle 33 and the opening in socket 34, through which the spindle passes, may be polygonal.

By the construction above described I am 35 enabled to get a large range of adjustment and can strike with greater or less force, according to the nature of the work. The cushioned hammer relieves the jar on the foot in operating the machine, as also the jar on the 40 mechanism, and causes very effective blows to be given without damage to machine or injury to operator.

The foot-lever is accessible from either side or from the front of the anvil, and no matter 45 where pressure is applied to the foot-lever the power is applied centrally. The rocking or swiveling movement of levers 10 gives a capacity for striking at angles and in positions not accessible to such hammers as move in 50 vertical guides or such hammers as swing in the same arc at all times, such hammers being well known. A power-hammer with elastic cushion to the peen is well known, but not, so far as I know, a hammer operated by a 55 foot-lever.

What I claim is—

1. In a machine of the character described, the U-shaped treadle, bars connected to each side thereof and to an intermediate lever pivoted to the anvil-support, the pivotally-supported hammer, and a link connecting the intermediate lever to the hammer-handle, all combined with an anvil substantially as described.

65 2. In a striking-machine of the character described, a treadle-lever at each side of the anvil-support, draw-bars connected thereto,

intermediate lever adjustably connected to the treadle-bars, and pivoted to the anvil-support, a pitman connected to such intermediate lever and adjustably connected to the hammer-handle, and a pivotal support on which the hammer swings, combined with an anvil substantially as described.

3. In a machine of the character described, 75 the handle-supporting bars having a swivel connection to the anvil-support, the hammer having its handle pivoted between said bars, means for operating the hammer, a lever pivoted to the anvil-support and connected to the 80 handle-supporting bars, and stops on the anvil-support by which said lever may be held in adjusted position to maintain the supporting-bars in adjusted position, all combined substantially as described. 85

4. In a foot-power hammer, the combination of the anvil and its support, the hammer-supporting bars swiveled to the anvil-support, the hammer pivoted between said bars and means for operating said hammer, and adjusting mechanism substantially as described 90 connected to the hammer-bars and to the anvil-support, by which the hammer-supporting bars may be turned in angular direction and held while the hammer strikes an oblique 95 blow, substantially as described.

5. In a machine of the character described, the hammer-supporting bars pivotally connected to the anvil-support, the hammer pivoted to said bars, and a foot-lever and connections for operating said hammer, and the standard notched near its lower end and pivotally connected to the hammer-supporting bars, said standard having its notches in position to engage a catch at the floor for vertical adjustment, substantially as described. 100

6. In a power-hammer, the anvil, support, and hammer-supporting bars pivotally connected to the anvil-support, the hammer pivoted between said hammer-supporting bars 110 and means for operating said hammer, the standard pivoted to said hammer-supporting bars and having notches near its lower end in position to engage a catch attached to the floor, and a spring connected to the hammer-handle and to the standard, adapted to lift the hammer and to draw a notch of the standard into engagement with the floor-catch, all combined substantially as described. 115

7. The hammer having a head with a recess 120 therein, an elastic cushion in said recess, a spindle embedded in said cushion and passing through a socket in the handle, and the handle-support and connections therefrom extending to the foot-lever whereby the shock 125 of operating the foot-lever is reduced by the elastic cushion, all substantially as described.

In testimony whereof I affix my signature in presence of two witnesses.

WILLIAM U. BURGETT.
